KEYBOARD KEY

Chester K. Marlow, Oakland, Calif., assignor to
 Friden Calculating Machine Co., Inc., a corpora-
 tion of California

Application October 28, 1949, Serial No. 124,095

5 Claims. (Cl. 197—102)

1

This invention relates to an improved means of securing a control key to a keyboard key stem, and more particularly to a means of pressure fitting a relatively heavy but slightly elastic control button to the associated key stem of a business machine or the like in such a manner as to produce at normal room temperatures a bond which will effectively resist forces tending to separate the finger button from the key stem during continued high speed operation of the keyboard.

In the construction and operation of automatic calculators, typewriters, and other similar machines, it frequently is desirable to return the control keys to their inactive or fully raised position as rapidly as possible, while at the same time enhancing the general appearance of the keyboard by providing control buttons having a shape and configuration adapted to conceal from view as much of the upwardly extending key stems as possible. This practice frequently increases the mass of the individual key assemblies to such an extent that keystones and other conventional securing means are not entirely satisfactory in preventing relative movement or separation between each such control key and its associated key stem, particularly in instances wherein it is desirable to directly apply resilient pressure to the base of each control button in order to accelerate the upward movement of each individual key assembly during release. The problem of establishing an effective bond between such a control button and its associated key stem becomes even more difficult to solve when the keyboard must be operated at relatively high speeds for prolonged periods while being at the same time subjected to higher than normal operating temperatures.

It is an important object of the present invention to provide a means of effectively securing a slightly elastic and relatively heavy control button to the corresponding keyboard key stem of a business machine or the like in such a manner as to produce an effective bond therewith, even though such a control key must be rapidly decelerated at the end of each high speed release operation.

It is also an object of the instant invention to provide a means of establishing at normal room temperatures an effective bond between a relatively elastic keyboard control button and its associated substantially inelastic key stem as a result of the application of downwardly directed pressure tending to press or force fit the button onto the key stem.

2

It is another object of the present invention to form a self-locking means for securing a relatively heavy plastic control button to its associated key stem in such a manner as to produce an effective bond and to substantially prevent relative movement between the button and the key stem whenever each such key assembly is frequently and repeatedly decelerated rapidly during release while being at the same time subjected to resilient pressures tending to separate the control button from its associated key stem.

It is still a further object of this invention to produce a means of effectively securing a slightly elastic control button to a relatively inelastic keyboard key stem in such manner as to establish a self-locking shear engagement therewith, which engagement is particularly adapted to effectively resist intermittently induced inertial forces tending to release the same and tending to cause a progressive separation of the control button from the key stem whenever the keyboard is operated at elevated temperatures for prolonged periods and at high speeds.

Further objects are to provide a construction of maximum simplicity, economy and ease of assembly and disassembly, also such further objects, advantages and capabilities as will fully appear and as inherently possessed by the device and the invention described herein.

The invention further resides in the combination, construction and arrangement of parts illustrated in the accompanying drawings, and while there is shown therein a preferred embodiment thereof, it is to be understood that the same is illustrative of the invention and that the invention is capable of modification and change and comprehends other details of construction without departing from the spirit thereof or the scope of the appended claims.

Referring to the drawings:

40 Fig. 1 is a plan view of a typical keyboard key assembly embodying the instant invention.

Fig. 2 is a transverse cross-sectional view taken along the lines 2—2 in Fig. 1.

45 Fig. 3 is a longitudinal cross-sectional view taken along the lines 3—3 in Fig. 1.

Referring now more particularly to the drawings, in which like reference numerals indicate like parts in the several views, there is shown a keyboard key assembly for an automatic calculator, typewriter, or similar business machine, which assembly includes a relatively elastic control button 20 adapted to be pressed onto and retained in self-locking engagement with the 50 similarly formed top portion 22 of a substan-

totally inelastic key stem 23. This manually de-
pressible control button 20 is molded or other-
wise formed of a thermo plastic material, such as
a suitable vinyl or polystyrene resin, which is
slightly elastic and has limited flow character-
istics when subjected to pressure at normal room
temperatures. Button 20 may be of modified cy-
lindrical shape and of a generally elliptical cross
section having flattened end portions 24 as illus-
trated in Fig. 1, or the keyboard control buttons
may be of circular or other suitable cross sec-
tion, if desired. A plastic inlay 25 in the form of
a suitable identifying numeral or letter is ce-
mented, molded, or otherwise embedded within
the upper contact surface 21 of each button, and
inlay 25 preferably is formed of a suitably col-
ored plastic which will provide a pleasing visual
contrast with the background color of the con-
trol button 20.

Key stem 23 preferably is punched or press-
formed from a relatively thick and rigid sheet
of metal, and has a rectangular, round, or other
suitably shaped aperture 26 disposed centrally
therein at a convenient distance below the upper-
most surface 27 of control button 20. Key stem
23, preferably but not necessarily, has a shoulder
28 extending inwardly from the opposing vertical
edges 29 thereof, which shoulder preferably forms
a seat for the button 20 when the top portion 22
of the key stem is pressed into engagement with
the coacting recess 30 molded or otherwise
formed interiorly within button 20. In some ap-
plications, however, it may be desirable to elimi-
nate the shoulder 28 so that the top portion 22 of
the key stem has a lateral dimension substan-
tially equal to the distance between the opposing
vertical edges 29 thereof, in which case the ver-
tically disposed interior slot or recess 30 is formed
within button 20 so that the top surface 27 of key
stem 22 seats against the coacting interior hori-
zontal surface 31 of recess 30. Thus, the configura-
tion of the interior cavity or recess 30 in the
control button 20 is substantially the same as
but slightly larger than the coacting top portion
22, so that the latter will normally be received
in a close running fit or in sliding engagement
therewith.

Means is also provided for securely retaining
the relatively heavy control button 20 in a pre-
determined position on key stem 23 and in effec-
tive self-locking engagement therewith, even
though resilient pressure of considerable magni-
tude is continuously applied to the lower surface
of the button for the purpose of accelerating the
upward movement and causing a rapid release
of the key assembly from its depressed position.
Referring now to Fig. 2, it will be apparent that
the thickness of the recess 30 formed interiorly
within button 20 is equal to or only slightly
greater than the thickness of key stem 23, and
that a resilient clip or rodlike spring member
35 has been interposed therebetween. This clip
preferably is of round cross-section and is formed
of spring steel, piano wire or similar resilient wire
having a diameter sufficiently greater than the
normal clearance between the outer surface 36
of key stem 23 and the coacting vertical wall
37 of recess 30 to provide a predetermined wedg-
ing or shear locking action whenever the control
button 20 is press-fitted onto the top portion 22
of the key stem. Clip 35 may, however, be pre-
formed from half-round spring wire, or may be
of square cross-section, if desired. The length
of clip 35 is substantially equal to the distance
between the top surface 27 of the key stem and

the upper surface 38 of aperture 26, and clip 35
has a U-shaped hook 39 at the lower end thereof
which is adapted to form a clasping or clamping
engagement with the adjacent portion of the key
stem which is immediately above aperture 26.
Thus, whenever clip 35 is installed on the key
stem in the manner illustrated in Figs. 2 and 3,
the shank 40 thereof is longitudinally disposed
along one surface of key stem 23, and the resil-
ient barb or prong 41 of clip 35 extends across
the top surface 27 of the key stem and projects
angularly downwardly therefrom to form a shear-
ing engagement between resilient member 41 and
button 20.

During the force fitting operation, clip 35 is
first installed on the upper portion of the key
stem with the lower hooked end 39 in engage-
ment with the top of aperture 26, and with the
upper resilient member 41 projecting downwardly
and outwardly from the top of the key stem as
shown in Fig. 2. The control button 20 is then
placed on top of the key stem, and thereafter the
assembly is placed in a suitable press so that
sufficient downwardly directed pressure may be
exerted on the upper surface 21 of the button to
force top portion 22 of the key stem into the
recess 30. As button 20 moves downwardly during
the press-fitting operation, spring member 41
is first forced inwardly in opposition to the in-
herent resilient action which normally urges the
element 41 into the extended position illustrated
in Fig. 2. Thus, clip 35 causes a plastic deforma-
tion within button 20 without removing material
therefrom or producing shear therein. After but-
ton 20 has been fully seated on the key stem,
however, the continuous resilient action exerted
by the member 41 on the adjacent plastic ma-
terial causes the plastic material within button
20 to flow underneath the member 41 and allow
it to gradually resume the normal angularly
downward position which is illustrated in Fig. 2.
Thus, spring element 41 functions as a resilient
barb or spike adapted to form an efficient and
highly effective self-locking shear engagement
between key stem 23 and the control button 20,
which engagement is caused by the plastic flow
and shear deformation which occurs within but-
ton 20 as a result of induced internal pressures
which are applied for prolonged periods of time
at normal room temperatures, and without the
necessity of permanently molding key 20 to key
stem 23 by the application of elevated tempera-
tures. Moreover, the efficiency of the bond thus
produced between each control button and its
associated key stem is increased by forces tend-
ing to separate button 20 from key stem 23 and
is not substantially diminished by the reduction
in the structural strength of the plastic button
which normally occurs whenever such a button
is subjected to higher than normal operating
temperatures for prolonged periods of time.

I claim:

1. In a keyboard key assembly, the combination
which comprises a key stem having an aperture
in the top portion thereof, a rodlike securing
member extending between and anchored by the
said aperture and the uppermost extremity of
the said key stem with an integral prong extend-
ing outwardly and angularly downward there-
from, and a slightly elastic finger button pres-
sure-fitted onto the said key stem thereby com-
pressing the said prong to effectively lock the
said finger button in a predetermined position
thereon as the said prong is resiliently urged out-
wardly so as to become imbedded within the

slightly elastic material within the interior of the said button.

2. In a keyboard key assembly, the combination which comprises a key stem having an aperture in the top portion thereof, a slightly elastic control button in engagement with the said key stem and pressure-fitted thereon, and a rodlike securing member hooked in the said aperture and having an integral resilient barb extending across and angularly downward from the top of the said key stem, the said barb becoming imbedded within the adjacent interior of the said button to establish an effective self-locking engagement therewith.

3. In a keyboard key assembly, the combination which comprises a key stem having an aperture in the top portion thereof, a relatively heavy plastic control button in engagement with the said key stem and pressure-fitted thereon, and a rodlike securing member interposed between the said button and the said key stem, the said member having a lower hook portion interlocked in said aperture and a resilient prong thereon extending across and angularly downward from the top of the said key stem and becoming resiliently imbedded within the adjacent interior of the said button to establish an effective shear resisting engagement therewith in such a manner that the securing action thereof is not substantially diminished by rapidly operating the keyboard while the latter is continually exposed to elevated operating temperatures.

4. In a keyboard key assembly, the combination which comprises a key stem having an aperture in the top portion thereof, a plastic control button slidably engaged with the said key stem and pressure-fitted thereon, and a resilient wire clip interposed between the said button and the said key stem, the said clip having at one ex-

10 tremity a normally angularly outwardly extending compressible spring member engaged with said key stem and the other substantially U-shaped extremity hooked on the edge of the said aperture, the said compressible spring member being resiliently urged into the adjacent ductile interior of the said button so that the effectiveness of the bond between the said key stem and the said button will be substantially increased by forces tending to separate the said button from the key stem.

15 5. In a keyboard key assembly, the combination which comprises a key stem having an aperture in the body portion thereof, a slightly elastic control button having a recess therein for engaging the said key stem, and a wire clip with a hook at one extremity engaging an edge of the said aperture for restraining movement of the said clip with respect to the said key stem, the said 20 wire clip having a resilient prong at its other extremity hooked over the end of the said key stem and resiliently urged angularly outward from the plane of the said key stem in such a manner as to effectively lock the said button in a predetermined position on the said key stem by becoming embedded within that portion of the ductile button which is immediately adjacent thereto.
